LIQUID FUEL INJECTION APPARATUS

Ralph Miller, Buffalo, N. Y.

Application October 20, 1942, Serial No. 462,673

7 Claims. (Cl. 137—153)

1

This invention relates to liquid fuel injection apparatus.

An object of the present invention is to provide improved fuel injection apparatus for use in high power internal combustion engines, adapted to provide correctly atomized fuel in metered quantity during the short duration of injection existing in engines especially of the high speed, high output type.

A further object is to provide an apparatus as aforesaid in which the valve mechanism of the injector nozzle is acted upon, in a desired manner, in both an opening and closing direction, by liquid under pressure from a common source of supply.

Other and further objects of the invention will appear from the following description, the accompanying drawings and the appended claims.

Referring to the drawings forming a part of this application, Figure 1 is an elevation of a preferred embodiment of the fuel injection apparatus of the present invention, the injector nozzle and a metering valve being shown partly in axial section, a part being broken away, part of a cam shaft mechanism forming part of an internal combustion engine also being shown, partly in transverse section; Fig. 2 is a view similar to Fig. 1, showing another embodiment of the invention, parts being broken away; Fig. 3 is an elevation, partly in axial section, of an injector nozzle and metering valve unitary structure; and Fig. 4 is a section on the line IV—IV of Fig. 1, parts being broken away.

Referring to Fig. 1 of the drawings, the fuel injection apparatus of the present invention, indicated generally by the reference numeral 1, includes a source of fuel supply 2, a metering valve 3, and an injector nozzle 4. The source of fuel supply 2 is indicated diagrammatically and may be any conventional apparatus adapted to supply fuel under constant pressure to a delivery pipe 5 which is branched to extend from the source 2 to the metering valve and to the injector nozzle, as will later more fully appear. For example, the source 2 may be a pump drawing fuel from a fuel tank (not shown) and pumping it through pipe 5, the pump being provided with means (not shown) for regulating the delivery pressure. It is contemplated that a single source 2 will provide for all the injector nozzles and metering valves of an engine, there being an injector nozzle and a metering valve for each cylinder. In such case pipe 5 will be a header, with branches for each of the nozzles and metering valves.

2

The metering valve 3 includes a hollow base 6 adapted to be secured to an appropriate part of the engine over a cam shaft 7 and cam 8, the cam having a cam face 8a. The cam engages a roller 9 journalled to a crosshead 10 which slides vertically in the hollow interior of base 6. A housing 11 is supported on base 6. It has an axial bore providing a cylinder 12 closed at the top by a cap 13, secured on top of the housing by a threaded connection, and open at the bottom to the interior of the base 6.

A reciprocating valve element 14 is disposed in the cylinder 12, its upper end being spaced from cap 13 and its lower end extending into the interior of base 6 and resting on top of crosshead 10. A coil spring 15, disposed in the cylinder 12 and compressed between the cap 13 and element 14, holds the element in engagement with the crosshead 10. The top of the element 14 is reduced to provide a spring retainer 16. A vent 17 is formed in the cap 13 and opens into the top of the cylinder 12.

Element 14 has a reduced portion 18 intermediate its ends, providing a chamber 19 defined by the reduced portion 18, the adjacent portion of the wall of the cylinder 12, a horizontal transverse shoulder 20 on the element at the upper edge of the reduced portion 18, and a curved transverse shoulder 21 on the element at the lower edge of the reduced portion 18. The shoulder 21 has two identical portions, one on each side of a diameter of the element. Each portion has a central high point from which point the portion curves downwardly on either side thereof.

Ports 22 and 23 are formed in the housing wall, port 22 being in continuous communication with chamber 19 and port 23 being adapted to open into the chamber 19 when element 14 is in lowered position. When the metering valve is adjusted for maximum fuel injection the high points of the shoulder 21 will be on the same diametrical plane of cylinder 12 as the port 23, as shown in Fig. 1.

Two other ports 24 and 25, below ports 22 and 23 respectively, are formed in the housing wall. Element 14 has another reduced portion 26, spaced below portion 18, providing a chamber 27 with which port 24 is in continuous communication and into which port 25 is adapted to open when the element 14 is in raised position. Chamber 27 is defined by the reduced portion 26, the adjacent portion of the wall of cylinder 12, a horizontal transverse shoulder 28 on the element at the lower edge of the reduced portion 26, and a curved transverse shoulder 29 on the element at the up-

per edge of the reduced portion 26. Shoulder 29 is parallel to shoulder 21, as is clearly shown in Fig. 1. The portion of the element between shoulders 21 and 29 forms a cut-off valve member 30 for closing port 23 instantaneously with opening of port 25, or vice versa.

Port 23 is formed by a bore extending across cylinder 12 so that there is a port 23a diametrically opposite port 23. Ports 23 and 23a are connected by a U-shaped passage 23b, best shown in Fig. 4, and formed by three bores closed at their outer ends by plugs. Port 25 is similarly made with a port 25a and passage 25b. Thus, when element 14 is in raised position, with valve member 30 closing both ports 23 and 25, oil under pressure in port 23 fills passage 23b and port 23a, and oil under pressure in port 25 fills passage 25b and port 25a, balancing the action of the oil under pressure on the element 14, thereby preventing an unbalanced lateral force thereon. Similarly, when element 14 is in lowered position, as shown in Fig. 1, oil under pressure in port 25 is balanced by oil under pressure in port 25a. Ports 23a and 25a are controlled by the shoulders 21 and 29 similarly to ports 23 and 25.

Element 14 is rotatable for adjustment to vary the timing of opening and closing of the ports 23-23a and 25-25a and to thereby vary the duration of the injection period. The adjusting mechanism, indicated generally by the numeral 31, is of substantially conventional design and will therefore be briefly described. It includes a gear 32 mounted in the housing 11 and supported by the base 6 against vertical movement and having depending spaced lugs 33 providing guide-ways for guides 34 on the element 14. In the present instance the guides 34 are shown as square-headed studs pressed into holes formed in the element. This permits axial movement of the element 14 relative to the gear 32 while insuring rotative movement of the element with the gear 32. Gear 32 is in mesh with a rack 35 which may be manually operated or operated by a governor (not shown), in a well-known manner, to rotate the gear and element for varying the opening and closing of the ports as aforesaid.

The injector nozzle 4 is adapted to be secured, in the usual manner, in a bore in a cylinder head of the internal combustion engine and to project therethrough opening into a cylinder thereof, the cylinder and cylinder head not being shown. The nozzle 4 includes a hollow housing 36 open at the bottom and closed at the top by a head 37 which is threaded partially into the hollow interior of the housing 36, thereby providing a chamber 38 below the head 37. A nozzle member 39 is disposed in the chamber 38 and extends through the bottom of the housing 36 and exteriorly downwardly therefrom. It is supported by means of shoulders 40 and 41 formed respectively on the housing 36 and nozzle member 39. A spacer or washer 42 is disposed between the top of the member 39 and the bottom of head 37, head 37 being screwed tightly against the washer 42 thereby holding the member 39 tightly in the housing.

The member 39 has injection jets 43 adapted to open into the engine cylinder. These injection jets open into a bore 44 provided at its upper end with a port or valve seat 45. An injection fuel chamber 46 is formed in the member 39 above the valve seat 45 and one or more fuel passages 47 (one being shown) open into chamber 46 and extend upwardly therefrom to an annular groove 48 formed in the upper face of the

member 39. An annular groove 49 is formed in the upper face of the washer 42 and is connected to the groove 48 by one or more fuel passages 50, one being shown.

5 A passage 51 formed in the head 37 opens at its lower end into groove 49 and extends upwardly through the head and opens through the outer face of the head. A chamber 52 is formed in the head adjacent the washer 42. A passage 53, 10 formed in the head, opens at its lower end into chamber 52 and extends therefrom upwardly through the head and opens through the outer face of the head. Washer 42 has a central orifice 54, which opens at the top into chamber 52 and which is tapered at the bottom providing a seat 54a diverging toward a cylinder 55 formed axially in the member 39, the cylinder 55 opening at its lower end into chamber 46.

A needle valve 56 for coaction with seat 45 20 is disposed in chamber 46. A pressure-responsive plunger 57 is disposed in cylinder 55 and is formed integral with valve 56. Valve 56 is of a smaller diameter than plunger 57 providing a shoulder 58. The upper end of plunger 57 is spaced from seat 54a, when the valve is closed, 25 providing a chamber 59 and permitting a small axial movement of the plunger 57, as will later be more fully described, to raise valve 56 off seat 45. As chamber 59, orifice 54 and chamber 30 52 are in continual communication they combine to form a loading fuel chamber. A stem 60 is disposed in orifice 54 in spaced relation with the wall thereof, and extends into chamber 59, and is formed integral with plunger 57. The 35 stem 60 is of smaller diameter than plunger 57 providing a shoulder 61. The upper end of stem 60 is disposed in chamber 52. A spring seat or washer 62 is supported on top of stem 60, and a coil spring 63 seats on this washer and is compressed between the washer and the opposite top wall of chamber 52. Washer 62 is of less diameter than chamber 52.

45 Plunger 57 is of the same diameter throughout so that throughout its travel it is affected only by pressures in chambers 46 and 59. When the apparatus is in the position shown in Fig. 1, that is to say, when the cam 8a is not in engagement with roller 9, the pressure in chambers 46 and 59 is similar and no leakage past plunger 57 50 can occur. During injection, when the pressure in chamber 46 is the higher, plunger 57 will be in engagement with the tapered seat 54a, closing orifice 54, and preventing leakage past plunger 57 and any resulting drop in pressure 55 in chamber 46. The engagement of plunger 57 and seat 54a is line engagement, so that the full top surface of the plunger 57, i. e., the shoulder 61 and top of stem 60, is subject to the pressure prevailing in chamber 52.

Delivery pipe 5 has a branch 64 connected to port 22 and a branch 65 connected to passage 51. If desired pipe 5 could go directly to either of these ports and a separate pipe go from the source 2 to the other port. A branched pipe 66 is connected at one end to passage 53 and extends through one branch 67 to port 23, and through another branch 68 to port 25. A pipe 69 is connected at one end to port 24 and at the other end opens to the exterior of the fuel injection apparatus to the atmosphere or to a place of low pressure, for instance to the fuel supply tank (not shown).

The operation of the fuel injection apparatus is as follows: Fuel injection chamber 46 is in continuous communication with source 2 as afore-

said so that fuel is maintained in chamber 46 at a constant pressure. This is true regardless of the operation of the metering valve. As shown in Fig. 1, the metering valve is in a position wherein needle valve 56 closes bore 44. At such time fuel under constant pressure from source 2 fills pipe 5, port 22 (through branch 64), chamber 19, port 23, pipe 66 (through branch 67), passage 53, chamber 52, orifice 54, and chamber 59. Thus fuel under the same pressure acts on both shoulders of plunger 57. However the fuel above plunger 57 acts on surfaces equal to the entire cross-sectional area of the plunger 57 (the pressure faces of shoulder 61 and stem 60), whereas fuel below plunger 57 acts on a lesser area, (the pressure faces of shoulder 58 and the portion of valve 56 in chamber 46), this latter area being smaller by the area of the bore 44 and seat 45. Thus the total fuel pressure holding the needle valve 56 closed is greater than the total fuel pressure acting to open same. Furthermore, the needle valve 56 is urged downwardly by the additive force of spring 63. Port 25 is closed from port 24 by valve member 30 as element 14 is in its lowermost position, as shown in Fig. 1.

The rotation of cam shaft 1 in the direction of the arrow *a* brings cam face 8a into engagement with roller 9, lifting crosshead 10 and element 14. Shoulder 21 closes ports 23-23a instantaneously with the opening of ports 25-25a by shoulder 29. As port 24 is opened to a place of lower pressure than the pressure of the fuel on shoulder 61 and stem 60, this latter pressure immediately drops, for instance to atmospheric pressure. However, as chamber 46 is in continuous communication with source 2 the pressure is maintained below the plunger 57, and this pressure exerts a force sufficiently greater than the force of the reduced pressure on shoulder 61, stem 60 and that of spring 63 to force the plunger 57 and needle valve 56 quickly upward, further compressing the spring 63. Bore 44 is thereby opened to chamber 46 and injection through jets 43 follows. Due to the quick opening of bore 44 and to the available supply of fuel under high pressure in chamber 46, only correctly atomized fuel is injected through jets 43 at the beginning of injection and no starting dribbling of fuel occurs.

Injection continues until element 14 moves downward sufficiently for shoulder 29 to close ports 25-25a and shoulder 21 to open ports 23-23a, once again opening chambers 59 and 52 above plunger 57 to the full pressure of the fuel in source 2.

When the needle valve is in raised position immediately after opening of ports 23-23a, the effective fuel pressures urging the plunger downward and urging the plunger upward are balanced, having the same areas to act upon, the area acted upon in a valve-opening direction then being the entire pressure face of valve 56 and the pressure face of shoulder 58. Only the spring 63 now exerts an effective force forcing the plunger 57 downward. However, as the needle valve 56 approaches the seat 45 the effective fuel pressure urging the plunger 57 upward is reduced, due to the throttling action as bore 44 is being closed, resulting in an increase in the effective fuel pressure force urging the plunger 57 downward, augmenting the force exerted by the spring 63, and effecting quick closing of bore 44 by the needle valve 56. This quick closing insures complete atomization of the fuel to the end of the injection period, preventing dribbling of fuel into the cylinder and thereby preventing the

accompanying undesirable injection conditions caused by such dribbling, as will later more fully appear.

A modification of the invention is exemplified by the fuel injection apparatus shown in Fig. 2, and indicated generally by the reference numeral 70. The apparatus differs from the apparatus 1 only in the metering valve and parts for operating same, the source of supply and the injector nozzle being the same as in Fig. 1, and where referred to, reference will be had to Fig. 1, similar reference numerals being employed.

The metering valve is indicated by the numeral 71. It includes a housing 72 having in its upper portion a central bore providing a chamber 73, and an axial bore of smaller diameter than the chamber 73 extending therefrom to the bottom of the housing, providing a cylinder 74. A shoulder 75 is provided at the juncture of chamber 73 and cylinder 74 and a valve seat 76 is provided therein. A port 77 is formed in the housing wall just below the seat 76 opening into the cylinder 74. Another port 78 is formed in the housing wall below port 77, also opening into the cylinder 74. A port 79 is formed in the housing wall opposite and opening into chamber 73. Chamber 73 is closed at the top by a two-piece plug and cap device 80 secured to the housing 72 by a threaded connection.

30 A valve member 81 is disposed in chamber 73 for coaction with seat 76. A stem 82, formed integral with the valve member is disposed in the cylinder 74, its lower end being above port 78. A balancing portion 83, integral with valve member 81, extends upwardly therefrom into a recess 83a formed in the plug of device 80, the portion 83 reducing the surface on top of member 81 upon which oil under pressure in chamber 73 can work. Recess 83a is vented to the atmosphere. 35 The stem 82 is reduced just below the valve member, providing with the opposite portion of the defining wall of cylinder 74, a chamber 84 in continuous communication with port 77. A coil spring 85 disposed in chamber 73 and compressed between the plug of device 80 and a washer supported on valve member 81, exerts a force urging valve member 81 toward seat 76. An axial bore 86 extends through the stem 82, valve member 81 and partially through portion 83, taking a right angle turn and opening into chamber 73.

40 A rod 87 is disposed in cylinder 74 below stem 82, its upper end being adapted to engage stem 82 and its lower end extending below housing 72 45 and engaging a wedge 88 pivoted to an arm 89 extending from a shaft 90, which may have its bearings (not shown) in any suitable part of the engine. In a multi-cylinder engine, wedge 88 may be wide enough to extend under all of the 50 metering valves. Wedge 88 may be adjusted manually or automatically, as desired, and have means (not shown) for holding it in an adjusted position.

45 Rod 87 is reduced adjacent port 78, providing a chamber 91 in continuous communication with port 78, chamber 91 being defined by the reduced portion of rod 87, the opposed portion of the cylinder wall, a portion of the bottom of stem 82 and the shoulder formed by the juncture of the reduced portion and the rest of the rod 87. Rod 87 is adapted, as will later more fully appear, to move downward out of engagement with stem 82, at which time valve member 81 will be forced into engagement with seat 76 by spring 85, and bore 86 will be opened to chamber 91 as well as

chamber 73. The top wall of rod 87 forms a valve member 92 for controlling the opening and closing of bore 86 to chamber 91.

The mechanism for operating the valve 71 further includes a cam shaft 93, a cam 94 thereon having a cam face 94a, and a rocker arm 95 pivotally supported on a shaft 96, which may have its bearings in any suitable part of the engine. The rocker arm bears at one end, by means of a roller 97, on cam 94 and at the other end engages the under face of wedge 88. A coil spring 98, supported on a seat 99, which may be on any suitable part of the engine, and bearing against a cap 100, which in turn engages the rocker arm 95 beneath wedge 88, exerts a force upwardly on the part of the rocker arm engaging wedge 88, the spring thereby keeping the arm in engagement with cam 94 and wedge 88 in engagement with rod 87. When cam face 94a engages roller 97, spring 85 moves valve member 81, stem 82 and rod 87 downward until valve member 81 engages seat 76. Thereafter rod 87 descends relative to stem 82, the pressure of the oil in bore 86 acting against valve member 92.

The source 2 is connected to passage 51 of nozzle 4 and to port 71 of valve 71 by a branched pipe 101 similar to pipe 5 of Fig. 1, there being a branch 102 connected to passage 51 and a branch 103 connected to port 71. A pipe 104 similar to pipe 69 of Fig. 1, and for a similar purpose, is connected to port 78. A pipe 105 connects port 79 with passage 53 of nozzle 4.

The apparatus of Fig. 2 is shown in the same operative position as the apparatus of Fig. 1, namely, just before injection. Further rotation of cam shaft 93 in the direction of arrow b will raise roller 97 and compress spring 98, permitting rod 87 to drop until valve member 81 seats on seat 76 and to further drop until bore 86 is opened to chamber 91. When this happens, pipe 104, chamber 91, bore 86, chamber 73, pipe 105 and passage 53 of nozzle 4 will be in communication, effecting a drop in pressure on top of shoulder 61 and stem 60 (of nozzle 4). As source 2 is in continuous communication with chamber 46 of nozzle 4 through branch 102 of pipe 101, injection will occur the same as in the apparatus of Fig. 1. When cam face 94a leaves roller 97, spring 98 forces rod 87 upward closing bore 86 and raising stem 82 until valve member 81 leaves seat 76. Source 2 will then be in communication through pipe 101 with both passages 51 and 53 of nozzle 4, communication with passage 53 being through port 77, chamber 84, chamber 73, and pipe 105.

Adjustment of the metering valve 71 is effected by moving wedge 88. Assuming the position in Fig. 2 is for maximum fuel injection, and it is desired to lessen the quantity of fuel injected, it is only necessary to move wedge 88 to the left as viewed in Fig. 2. This will effect a further movement upward of rod 87 and stem 82 (the cam 94 remaining in the position shown) and will therefore retard the time at which rod 87 opens bore 86 to chamber 91, or, in other words, will retard the beginning of injection. Similarly it will hasten the termination of injection the same amount that it retards beginning, so that the injection period will be shortened.

The fuel injection apparatus shown in Fig. 3, indicated generally by the reference numeral 106, is similar to the apparatuses 1 and 70 in that it has three parts, the parts being the source of fuel supply (not shown in Fig. 3), the metering valve 107 and the injector nozzle 108, the valve

107 and nozzle 108 being secured together and having common parts, thereby forming a unit injector indicated by the numeral 109. Apparatus 106 is for employment in engines having an overhead cam shaft (not shown), as will presently appear.

Injector 109 includes a hollow body 110 on which is threaded, at the bottom thereof, a cap 111 for a purpose presently to appear. Body 110 has at its top a central chamber 112, therebelow another chamber 113 of lesser diameter and therebelow an axial bore providing a cylinder 114 of lesser diameter than chamber 113, there being a shoulder 115 between chambers 112 and 113 and a shoulder 116 between chamber 113 and cylinder 114.

Cap 111 is hollow providing a chamber 117 between its bottom wall 118 and the bottom of body 110. A central orifice 119 is formed in wall 118, and being of lesser diameter than chamber 117, provides a shoulder 120 therebetween.

A valve element 121 is disposed in cylinder 114, chamber 113 and chamber 112. A washer 122 is secured to the upper end of element 121 by a split snap ring 123, and washer 122 supports a crosshead or sleeve 124, which engages the top of element 121 and is adapted to reciprocate in chamber 112 and to be acted upon by a rocker arm of an overhead cam shaft mechanism (not shown). An orificed washer 125 is supported on shoulder 115, fitting freely around element 121, and a coil spring 126 is compressed between washers 122 and 125, urging element 121 upward and holding sleeve 124 in engagement with the rocker arm (not shown) in a well-known manner.

Apparatus 106 includes an adjusting mechanism, indicated generally by the reference numeral 127, which is substantially like the mechanism 31 of Fig. 1 and therefore it will be but briefly described, using the same numerals as in Fig. 1 with an accent added. Mechanism 127 includes a gear 32' having upwardly extending spaced lugs 33'. Gear 32' is supported on shoulder 116 and fits freely around element 121. Guides 34' formed integrally with the element 121 slide in the guideways formed by the lugs 33'. A rack 35' meshes with gear 32'.

The port-controlling part of element 121 is similar to the corresponding part of element 14 (Fig. 1), taking into consideration that in Fig. 3 the cam operates from the top, and therefore it will be but briefly described, using the same numerals as in Fig. 1 with an accent added. There are reduced portions 18' and 26'; shoulders 21' and 29'; shoulders 20' and 28'; and chambers 19' and 27'. There is further an axial bore 128 extending from the bottom face of element 121 to the reduced portion 26' and opening into the chamber 27' by means of a radial bore 129. The bottom face of element 121 is spaced from the bottom of the body 110 providing a chamber into which bore 128 opens at its lower end.

Nozzle 108 is, in the main, similar to nozzle member 39 of Fig. 1. It has a portion disposed in chamber 117 and resting on shoulder 120, the remainder of the nozzle extending through orifice 119 and therebeyond.

A washer or spacer 130 is disposed in chamber 117 between the nozzle 108 and bottom of the body 110. Washer 130 is shown made in two pieces but it may be made in one piece if desired.

Nozzle 108 has jets 131, a bore 132 communicating therewith, a port or valve seat 133 at the upper end of the bore, an injection fuel chamber

134 above the valve seat, one or more passages 135 (two being shown) leading from chamber 134 to a groove 136 in the upper face of the nozzle 108, an axial bore providing a cylinder 137 opening at its bottom into chamber 134 and at its top through the top face of the nozzle, a needle valve 138 supported on seat 133 for co-action therewith, and a plunger 139 integral with valve 138 and disposed in cylinder 137 in spaced relation at its upper end with washer 130, washer 130 having a recess for a spring providing, with the space in cylinder 137 above plunger 139, a loading fuel chamber 140. A coil spring 141 is disposed in chamber 140 and compressed between the top of the plunger 139 and a washer 130 acting to force plunger 139 downward. The lower end of the recess is flared, providing a tapered seat 142 for the same purpose as seat 54a (Fig. 1). As aforesaid, washer 130 is made in two pieces, the lower piece 144 being provided with the seat 142. A shoulder 143 is provided between valve 138 and plunger 139. A dowel 145 secures body 110 and the top piece of washer 130 against relative rotation.

A short groove 146, formed in the upper face of washer 130, is connected by a passage 147 to chamber 140, and another short groove 148, also formed in the upper face of washer 130, but spaced from groove 146, is connected by a passage 149 to groove 136, passage 149 including a bore 149a in the top piece of washer 130, a groove 149b in the top face of piece 144, and two bores 149c connecting grooves 149b and 136.

The body 110 has formed therein a plurality of passages, as will presently appear. These passages may be formed by boring and are so shown in the drawing. Outer ends of some of the bores are closed by plugs 150 in a well-known manner.

A passage 151 is formed in the wall of body 110, opening therethrough adjacent the mechanism 127 and extending downwardly through the body to a point adjacent chamber 19', where it is branched, a branch 152 opening into groove 148, and a branch 153 opening into chamber 19'. Passage 151 is connected by a pipe (not shown) to a source of fuel supply (not shown) similar to source 2 of Fig. 1, the pipe in this embodiment not being branched.

A passage 154 is formed in the wall of body 110, opening therethrough below mechanism 127 and extending to chamber 27'. Passage 154 is connected to a place of low pressure similar to port 24 in Fig. 1. As is clearly shown in Fig. 3, passage 154 is U-shaped, passing through cylinder 114 twice (in opposite directions). An annular groove 155 is formed in the body 110 around cylinder 114 and in communication with passage 154 (forming a part thereof) so that the upper portion of valve element 121 will not stop the flow through passage 154 and so that oil in groove 155 will lubricate element 121.

The body includes another branched passage 156, opening at its lower end in groove 146 and having a branch 157 adapted to open into chamber 19' and a branch 158 adapted to open in chamber 27'. Branches 157 and 158 are made similar to ports 23 and 25 (Fig. 1) for balancing lateral oil pressure forces on the element 121. A valve member 159, formed by the portion of element 121 between shoulders 21' and 29' controls the opening and closing of branches 157 and 158, as will presently appear.

The operation of the apparatus of Fig. 3 is as follows: Fuel under pressure from the source of

fuel supply passes through passage 151, which is the only passage in direct communication with the source. Passage 151 is in continuous communication with the source and with branch 152, groove 148, passage 149, groove 136, passages 135 and chamber 134. Thus fuel under constant pressure is continuously in chamber 134, for injection and for exerting a lifting force on plunger 139. Branch 153 opens continuously into chamber 19' which therefore is in continuous communication with the source of fuel supply.

Valve element 121 is shown in Fig. 3 adjusted for maximum fuel injection. Element 121 is in full raised position, with chamber 19' in communication with branch 157. Thus fuel, under the pressure of the source of fuel supply, fills chamber 140 and acts on top of plunger 139, chamber 140 being in communication with branch 157 through passage 147, groove 146 and passage 156. Branch 158 is closed by valve member 159 of element 121. Therefore the pressure of the fuel acting on shoulder 143 and on top of plunger 139 is the same and plunger 139 is held downward, as the fuel under pressure in chamber 140 acts on a greater surface of plunger 139 than the fuel under pressure in the chamber 134, as in the nozzle of Fig. 1, and the spring 141 augments this closing pressure.

Downward movement of element 121 by the cam shaft rocker arm mechanism (not shown) acting on sleeve 124, effects closing of branch 157 simultaneously with opening of branch 158. Pressure in chamber 140 is thereby reduced as it is connected to the atmosphere or some place of low pressure by means of passage 147, groove 146, passage 156, branch 158, chamber 27', and passage 154. Pressure in chamber 134 then lifts plunger 139 and effects injection, which continues until the cam shaft mechanism permits element 121 to rise, due to the action of spring 126, to a position opening branch 157 to chamber 19'. During downward movement of element 121, the space below element 121 is vented, preventing pressure rise therein, through bores 128 and 129, chamber 27' and passage 154.

It will be seen that the operation of the apparatus of Fig. 3 is substantially like that of Fig. 1 and no further description thereof is deemed necessary.

It will be seen from the foregoing description of three embodiments of the present invention, that the functions and ends attained by each of these embodiments are the same, and that therefore the advantages sought from the present invention are common to all three embodiments.

More specifically, in each embodiment the injection fuel chamber is in continuous communication with a source of fuel supply delivering fuel at a constant pressure. By constant pressure is meant that the source of fuel supply delivers fuel at a constant pressure to the injection fuel chamber below the valve-lifting plunger of the nozzle so that before, during and after injection this chamber is filled with fuel at a constant pressure. Of course, at low output or low speed this pressure may be lower than at high output or high speed, and the source of fuel supply may have automatic adjusting means for accomplishing this. One given constant pressure may be employed throughout a given range of engine output, and then a higher constant pressure for a higher given range, and so on.

Fuel under constant pressure is delivered to chambers both below and above the nozzle valve-

actuating plunger, and works on a greater surface, when the valve is closed in a valve-closing direction so that the valve is hydraulically held closed and hydraulically actuated in a closing direction. This hydraulic feature is augmented by a coil spring urging the plunger in a closing direction. While the fuel actuating the plunger in a valve-closing direction is at a constant pressure, it is alternately in communication with the source of fuel supply and with the atmosphere or place of low pressure, so that its action upon the plunger is intermittent.

As previously described in relation to the operation of the apparatus of Fig. 1, but now describing all three embodiments, the nozzle valve is initially moved in a closing direction by the coil spring, until the pressure of the fuel acting to move the plunger in a valve-opening direction is throttled. Thereafter, the pressure of the fuel acting to move the plunger in a valve-closing direction predominates, this latter pressure and the coil spring effecting a quick, sharply defined termination of injection, preventing dribbling of fuel into the cylinder, and thereby preventing the consequential poor combustion features common where dribbling occurs. Dribbling is prevented, as aforescribed, at the beginning of injection by the constant high pressure fuel in the fuel injection chamber and by the quick raising of the valve of the injector nozzle.

In former injection apparatus, where it has been attempted to sharply terminate injection when the engine is running at high output, pressure surges have occurred in the fuel delivery line, and these surges often result in a reopening of the injection valve at a wrong time, and in a breaking of pipe line connections. These surges are produced by the high frequency intermittent pressures occurring in the lines between the injection pump and nozzle and is greatly augmented by the restriction in size of injection fuel passages, pipes and chambers, such restriction being required where the fuel pressure acting to open the injection valve is intermittent. In accordance with the present invention, injection fuel passages, pipes and chambers need not be restricted, but, on the other hand, because they are filled with fuel under constant pressure, may be made large enough so that pressure surges are not set up. Thus after injections and pipe breakage are prevented.

While there have been hereinbefore described approved embodiments of this invention, it will be understood that many and various changes and modifications in form, arrangement of parts and details of construction thereof may be made without departing from the spirit of the invention and that all such changes and modifications as fall within the scope of the appended claims are contemplated as a part of this invention.

The invention claimed and desired to be secured by Letters Patent is:

1. Liquid fuel injection mechanism comprising a housing having a longitudinal cylinder for a plunger, a fuel chamber opening into said cylinder at one end thereof and having an opening opposite said cylinder providing a valve seat, and a passage opening into said chamber for directly and continuously supplying injection fuel under pressure thereto; a plunger mounted in said cylinder for free sliding movement having an end, including a shoulder, adjacent said chamber, and a stem extending therefrom terminating in a valve for said seat, said end providing a fuel pressure surface, the opposite end of said plunger

being adjacent the opposite end of said cylinder and providing a dual element serving as both a fuel pressure surface and a valve, said housing further having a seat element at said opposite end of said cylinder for said dual element and engaging with the peripheral edge of the adjacent end of said plunger and a fuel passage opening through said seat element for alternate transmission and release of fuel pressure respectively to and from said dual element, said dual element being closed when said stem valve is open, said dual element pressure surface, when said dual element valve is closed, being at least equal in effective pressure area to the effective pressure area of said plunger shoulder-stem end when said stem valve is open; and a spring urging said dual element from said seat element, said plunger operating to control said stem valve through cooperation of said spring and the pressures of said fuel upon said surfaces.

2. Liquid fuel injection mechanism comprising a housing having a longitudinal cylinder for a plunger, a fuel chamber opening into said cylinder at one end thereof and having an opening opposite said cylinder providing a valve seat, and a passage opening into said chamber for supplying fuel under pressure thereto; a plunger mounted in said cylinder for free sliding movement having an end, including a shoulder, adjacent said chamber, and a stem extending therefrom terminating in a valve for said seat, said end providing a fuel pressure surface, the opposite end of said plunger being adjacent the opposite end of said cylinder and providing a dual element serving as both a fuel pressure surface and a valve, said housing further having a seat element at said opposite end of said cylinder for said dual element and a fuel passage opening through said seat element for alternate transmission and release of fuel pressure respectively to and from said dual element, said last mentioned passage including a chamber spaced from said seat element, and said dual element including a shoulder and a stem extending into said last mentioned passage and terminating in a spring seat in said passage chamber; and a compression spring in said passage chamber supported on said spring seat, urging said dual element shoulder from said seat element, said plunger operating to control said stem valve through cooperation of said spring and the pressures of said fuel upon said surfaces.

3. Liquid fuel injection mechanism comprising a housing having a longitudinal cylinder for a plunger, a fuel chamber opening into said cylinder at one end thereof and having an opening opposite said cylinder providing a valve seat, and a passage opening into said chamber for directly and continuously supplying fuel under pressure thereto; a plunger mounted in said cylinder for free sliding movement having an end, including a shoulder, adjacent said chamber, and a stem extending therefrom terminating in a valve for said seat, said end providing a fuel pressure surface, the opposite end of said plunger being adjacent the opposite end of said cylinder and providing a dual element serving as both a fuel pressure surface and a valve, said housing further having a seat element at said opposite end of said cylinder for said dual element engaging in a line contact with outside peripheral end edge of said plunger and a fuel passage terminating in a chamber adjacent to and opening through said seat element, said last mentioned passage being for alternate transmission and release of fuel

13

pressure respectively to and from said dual element; and a compression spring in said passage chamber and engaging on said dual element for, urging said dual element from said seat element, said plunger operating to control said stem valve through cooperation of said spring and the pressures of said fuel upon said surfaces.

4. Liquid fuel injection mechanism comprising a housing having an injection chamber, a single discharge passage leading from said chamber with an inwardly facing valve seat in said passage and controlling all movement of fluid out of said chamber, and a piston chamber opening into said injection chamber and approximately aligned with, and of greater cross sectional area than, said seat at said opening, a piston element slidingly fitting said piston chamber at the end opening into said injection chamber and having at one end a valve portion reduced in cross section and engaging with said seat when said piston element moves toward the seat to prevent discharge of fuel from said injection chamber through said passage, a connection directly connected to said injection chamber for continuously supplying thereto, fuel under injection pressure, said housing having a control chamber at the end of said piston chamber opposite the end of said injection chamber, a second valve seat in said control chamber engaged by the outer peripheral end edge of said piston element in piston element maximum diameter line to line contact therewith when that element moves away from said first valve seat, and from which its separates when said piston element moves to engage said first valve seat, a spring acting on said piston element and urging it in a direction to engage said first valve seat, and a valve controlled duct leading to said control chamber, and opening therein through said second valve seat, whereby variation of the fluid pressure in said control chamber may control the injection of fluid through said discharge passage.

5. Liquid fuel injection mechanism comprising a body having a plunger space with an injection chamber at one end and a control chamber at the other end, said body having a single discharge passage from said injection chamber with an outlet valve seat facing the injection chamber, a piston element sliding endwise in said space and having at one end, a valve portion reduced in cross section and extending across said injection chamber, into engagement with said seat at one end of movement of said element, said body having a concave seat in said control chamber engaged by the periphery of the end edge of the adjacent end of said element in piston element maximum diameter line to line contact therewith at the other end of movement of said element in said space, a spring urging said element towards said outlet seat, a duct connected to said injection chamber for supplying thereto injection fuel directly and continuously under injection pressure, and a connection to said control chamber through the passage defined by said concave seat for supplying against the adjacent end of said element a fluid under a variable pressure, while injection pressure remains in said injection chamber.

6. Liquid fuel injection mechanism comprising a body having a plunger space with an injection chamber at one end and a control chamber at the other end, said body having a single discharge passage from said injection chamber with an outlet valve seat facing the injection chamber, a

14

piston element sliding endwise in said space and having at one end, a valve portion reduced in cross section and extending across said injection chamber, into engagement with said seat at one end of movement of said element, said body having a valve seat in said control chamber enclosing an area, by line to line contact of piston element maximum diameter with the other end of said piston element, at least as large as the effective opening pressure area on said element in said injection chamber when said element is unseated from said outlet valve seat, a duct connected to said injection chamber for supplying thereto fuel directly and continuously under injection pressure, and means for supplying at will to said element in said control chamber, a force urging it in a direction to engage said outlet seat, including a duct opening through the area defined by said seat in said control chamber, for supplying fluid under pressure to the adjacent end face of said piston element.

7. Liquid fuel injection mechanism comprising a housing having a longitudinal cylinder for a plunger, a fuel chamber opening into said cylinder at one end thereof and having an opening opposite said cylinder providing a valve seat, and a passage opening into said chamber for directly and continuously supplying injection fuel under pressure thereto; a plunger mounted in said cylinder for free sliding movement having an end, including a shoulder, adjacent said chamber, and a stem extending therefrom terminating in a valve for said seat, said end providing a fuel pressure surface, the opposite end of said plunger being adjacent the opposite end of said cylinder and providing a dual element serving as both a fuel pressure surface and a valve, said housing further having a seat element at said opposite end of said cylinder for said dual element and a fuel passage opening through said seat element for alternate transmission and release of fuel pressure respectively to and from said dual element, said seat element being concave and said plunger opposite end at its peripheral edge being engageable in line contact of maximum diameter with said concave seat element whereby substantially line contact between said elements is provided when said elements are engaged to close the fuel passage opening through said seat element; and a spring urging said dual element from said seat element, said plunger operating to control said stem valve through cooperation of said spring and the pressures of said fuel upon said surfaces.

RALPH MILLER.
